M. SERVAIS.

APPARATUS FOR CUTTING TUBES.

APPLICATION FILED MAR. 29, 1921.

1,431,546.

Patented Oct. 10, 1922.

Inventor:
Mathieu Servais
By Lawrence Langner
Attorney.

UNITED STATES PATENT OFFICE.

MATHIEU SERVAIS, OF LIEGE, BELGIUM.

APPARATUS FOR CUTTING TUBES.

Application filed March 29, 1921. Serial No. 456,762.

To all whom it may concern:

Be it known that I, MATHIEU SERVAIS, manufacturer, a subject of the King of Belgium, residing at 38 Rue Nysten, Liege, Belgium, have invented certain new and useful Improvements in Apparatus for Cutting Tubes (for which I have filed an application in Belgium 30th day of April, 1920, and in France 15th day of February, 1921); and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

The present invention relates to an apparatus for cutting tubes of that type in which the tube to be cut is clamped between rollers one carried by the operating lever and the other carried by a member slidably upon the said lever and adapted to be secured on this lever. The present invention particularly relates to means for controlling the movement of the cutter.

According to the present invention this cutter is fixed on a screw-threaded rod which is prevented from rotating and only capable of being displaced axially, the screw-thread of this rod being engaged with an internal screw-thread provided in the centre of a toothed wheel whose axial displacement is prevented and whose rotation is effected by a worm operated by hand.

The accompanying drawings represents by way of example one method of carrying out the invention.

In these drawings:

40 Figure 1 is a perspective view of the apparatus, partly broken away.

Figure 2 is a horizontal section taken through the plane of the worm.

Figure 3 is a vertical section on A—B, Figure 2.

The tube to be cut is clamped between rollers such as 1 and 2. The rollers 1 are carried by a member 3 slidably on the rod 4 constituting the operating lever. At the end of this lever is fixed a member 5 carrying the rollers 2 and the controlling mechanism of the cutter. The member 3 is fixed in the

desired position with respect to the rod 4 by means of the clamping screw 6 operated by the handle 7.

The member 5 is of U-form secured at its base to the rod 4 and each of its operating mechanism is arranged between the two branches of the U.

The cutter 8 is fixed on a cheek 9 integral with a screw-threaded shaft 10 capable of being displaced axially but incapable of rotation. The rotation of this shaft 10 is prevented by reason of the cheek 9 engaging two ribs, 27, 28 of the member 5. The screw-thread of this shaft is engaged within a corresponding internal screw-thread formed in the centre of a toothed wheel 11 whose rotation causes the displacement of the shaft 10. The toothed wheel 11 engages grooves 12 and 13 in cheeks 14 and 15 fixed to each side of the member 5. By reason of this arrangement in the grooves 12 and 13 the axial displacements of the toothed wheel 11 are prevented. The rotation of the toothed wheel 11 is effected by a worm 16 actuated by hand by means of a winged head 17 fixed on the axis of the said worm 16.

The securing of the cheeks 14 and 15 is effected by means of bolts 18 and 19 and is completed by the fact that these cheeks are traversed by the axis of the worm 16.

The cheeks are provided with flanges 20 and 21 embracing the guides 22 carried by the member 3.

The cutter 8, in the arrangement represented, is constituted by a disc provided with a cutting edge. It is obvious that the disc can be provided with a plurality of cutting edges.

The fixing of the cutter is effected in the following manner: The cheek 9 is provided with a screw-threaded pin 25 on which the disc is fixed. The latter carries a toothed or serrated collar 23 whose teeth engage those of a toothed ring 24 carried by the said cheek 9. The reciprocal engagement of the teeth is assured by a nut 26 screwed on the pin 25.

What I claim is:

100 Apparatus for cutting tubes, comprising rollers for gripping the tube at three points circumferentially thereof, a screw threaded shaft, a cutter fixed thereon said

shaft being prevented from rotating but capable of axial displacement, a toothed wheel having an internal screw-thread arranged in its center and engaged by said shaft, the axial displacement of said toothed wheel being prevented, and a hand operated worm for effecting the rotation of said wheel.

In testimony whereof I affix my signature in presence of two witnesses.

MATHIEU SERVAIS.
